UNITED STATES PATENT OFFICE.

CHARLES HITCHCOCK AND EUGENE M. CHAPMAN, OF HOLYOKE, MASSACHUSETTS.

BOTTLE-STOPPER.

SPECIFICATION forming part of Letters Patent No. 394,182, dated December 11, 1888.

Application filed April 23, 1888. Serial No. 271,617. (No model.)

To all whom it may concern:

Be it known that we, CHARLES HITCHCOCK and EUGENE M. CHAPMAN, citizens of the United States, residing at Holyoke, in the 5 county of Hampden and State of Massachusetts, have invented new and useful Improvements in Bottle-Stopper Mechanism, of which the following is a specification.

This invention relates to bottle-stopper mechanism, the object being to provide for use on bottles containing effervescent compounds and other liquids improved stopper mechanism; and the invention consists in the peculiar construction and arrangement of 15 the valve of the stopper and its operating mechanism, all as hereinafter fully described, and pointed out in the claims.

In the drawings forming part of this specification, Figure 1 is a side elevation of the 20 nose of a bottle having applied thereto stopper mechanism constructed according to our invention, said figure showing the case containing said mechanism and parts of the latter in section and a portion of said mechanism in side elevation, all as hereinafter fully 25 described. Fig. 2 is a transverse section of the stopper-case on line $x-x$, Fig. 1, looking upward, in which figure certain parts are indicated in dotted lines. Fig. 3 is a top plan 30 view of the stopper, showing the outer side of the valve when the latter is shut.

In the drawings, 2 indicates the end of the nozzle of a bottle to which the herein-described stopper mechanism is attached. A 35 metallic case, 3, preferably of brass, of cylindrical form, is provided with an enlarged base, 4, in which is placed a rubber or similar packing-ring, 5, said ring being interposed between the end of the nozzle 2 of the bottle 40 and said base, and by a suitable locking-ring, 6, the said case is secured to the bottle in the position shown in Fig. 1. The said locking-ring 6, which is shown in section in Fig. 1, is in practice made of metal, preferably in two 45 segmental sections, one of which is shown in said figure, which sections are hooked onto the base 4 in the manner shown, and engaged with the under edge of the collar on the bottle-nozzle 2 after said base is placed in position on said nozzle, and then the said two

segments of the ring are united by soldering or other similar means.

The discharge end of the stopper-case 3 is reduced in diameter at z to form a valve-seat at that point, and the extreme end of said case is made to project slightly above said valve-seat in order that the valve may not be hit or interfered with when one bottle is placed on another, as is sometimes done to pack them for transportation. Said case is 55 substantially of tubular form.

Near the lower end of the stopper-case 3 an opening is made through the side thereof, in which is rigidly secured a metallic tube, 7, standing at right angles to the length of said case and extending nearly to the center thereof. Said tube 7 has a flange, 8, around its inner end, and on the opposite sides of said flange are cemented two packing-rings, 9 and 10, preferably of rubber or of other 65 similar yielding substance.

A metallic packing-box, 12, preferably of cylindrical form, is placed on the tube 7, and incloses the flanged end of the latter and the said packing-rings, said packing-box having 75 a free movement longitudinally on said tube 7. The said packing-box 12 is first made in cup shape, and the outer end of the tube 7 is passed through one side of it before said tube is secured to the stopper-case, as aforesaid, 80 and then the head o of said packing-box is soldered tightly to the end of said box. A plunger, 13, having a head thereon, as shown, is fitted to move freely within said tube 7, its inner end acting against the inner side of the 85 head o of the packing-box to move the latter longitudinally on the tube 7.

The purpose of the above-described construction of the flanged tube 7, having the packing-rings 9 and 10 cemented to the flanges 90 thereof, and the packing-box 12, inclosing the flanged end of said tube and said packing-rings, is to provide a gas-check or means for preventing any of the contents of a bottle to which the within-described stopper may be 95 applied from escaping between the plunger 13 and its inclosing-tube, said plunger being adapted to be moved endwise by pressing against its headed end to operate devices for opening the valve of the stopper by moving 100

said packing-box against the end of a lever, as below described. A spring acting against said lever, together with a certain force derived from the effervescent contents of the bottle, 5 serves to move said packing-box and plunger in the opposite direction when the latter is left free to so move. To the end that the packing-rings 9 and 10 may act efficiently for preventing any leakage around the tube 7 within 10 the packing-box 12, and between the edges of said rings and the walls of said packing-box, and thence between the plunger 13 and the inner walls of the tube 7, said rings are made so easily compressible that under the 15 action of more or less pressure their peripheries are made to impinge against the walls of said packing-box, thereby preventing said leakage and not producing so much frictional resistance to the said movement of the packing-box as to interfere with the operation of the valve devices hereinafter described.

It is obvious that ordinary and well-known means may be employed in connection with the plunger 13 and the tube 7, within which 20 said plunger moves—such as an ordinary stuffing-box like those in common use on valve-spindles and hubs applied to the outer end of said tube 7 to prevent the said leakage between said tube and plunger; but said stuffing-box provided with the common interior packing would cause more friction than do the above-described packing-box 12 and packing-rings, and therefore prevent the requisite 25 comparatively free sliding movement of the plunger.

The valve 21 of the stopper is of disk form, as shown in Fig. 3, having an annular groove around its border, in which is placed a packing-ring, 23, preferably of rubber, which packing-ring has a bearing against the inclined valve-seat α of the stopper-case, as clearly 30 shown in Fig. 1, when the valve is shut, as there shown, the upper side of the valve being of slightly less diameter than that portion 35 of said case above the seat, so that nothing but said packing shall strike the end of the stopper when the valve is shut, thereby insuring a tight fit between the packing and valve-seat. Said valve has fixed to its under 40 side, near one edge thereof, a downhanging arm, 24. The valve may be made of sheet or cast metal, the former being preferable because of its lightness.

A lever, 14, having substantially three arms, 45 e , v , and 20, is hung by the end of said arm v on a pivot-pin, 15, fixed in a projection, c , on one side of the stopper-case 3, on which pin said lever is capable of a vibratory motion in a vertical plane, being actuated by the above-described movement of the plunger 13 and the packing-box 12, actuated by the plunger, whereby said box is moved against the lower 50 end of the arm e of said lever. A spring, below described, moves said arm e of the lever 55 in the opposite direction indirectly through the movement of the valve 21. The said arm 20 of the lever 14 is pivoted to the under side

of the valve 21 by a pin, 22, fixed transversely across said valve to one side of a center line from border to border of said valve.

A bar, 16, (see Fig. 2,) is fixed transversely across and within the stopper-case 3, beneath which is located the main part of said lever 14, and on said bar 16 is a double coiled spring having downwardly-projecting ends 18, which bear against the inner side of the stopper-case, and having a looped end, 19, extending upward against the under side of the valve, said looped part of the spring having the arm 20 of the lever 14 extending through it. 70 The said spring 17 serves, by the bearing of its arm 19 against the valve, to swing the latter to the shut position shown in Fig. 1, and in so doing to cause the lever 14 to vibrate on its pivot 15, thereby forcing the arm e of said lever against the end of the packing-box 12, whereby the latter and the plunger 13 are moved to the position shown in Fig. 1 when the plunger is left free to be so actuated. The 80 said arm 24 on the under side of the valve 21 has its lower end engaging with the said bar 16, on which the spring 17 is supported, and when the plunger 13 and the packing-box 12 are moved toward and against the arm e of lever 14 to open the valve of the stopper, 85 whereby said lever and valve are brought to the positions shown in dotted lines in Fig. 1, (wherein the valve is shown nearly fully open,) said arm 24 is brought into engagement with the side of said bar 16, thereby causing a 90 quickly-vibratory movement of the edge of the valve opposite to that near which said arm is attached away from the valve-seat, and the release of the plunger, as aforesaid, permits the valve to be automatically shut by 95 the action of the spring 17, as aforesaid.

By pivoting the valve to one side of its center, as above described, a more unobstructed opening for the discharge of the contents of a bottle is provided for between the valve 100 when opened and the opposite side of the opening at the end of the case than would be had were the valve centrally pivoted.

The valve 21, constructed as above described, has a plane outer face, as shown in Fig. 3, whereby provision is made for applying to said face by suitable means a word or words, as shown in said last-named figure, to indicate the contents of the bottle to which said stopper is attached.

What we claim as our invention is—

1. Bottle-stopper devices consisting of a case, 3, having a valve-seat therein, a valve within said case to shut against said seat, having an arm projecting from its inner side, a 115 lever pivoted to one side of said case capable of a vibratory motion in a plane at right angles to the face of said valve, and having a pivotal connection therewith by one arm and having another arm extending toward the base 120 of the case, a bar fixed transversely across said case, with which the arm on said valve engages, a spring hung on said transverse bar having an engagement with the under side of

- the valve to swing it toward its seat, and a plunger passing through the side of said case opposite the end of the said downwardly-extending arm of said lever, combined and operating substantially as set forth. 5
2. The tubular case 3, having a valve-seat at one end, the tube 7, having a flange on its inner end passing through and fixed in the side of said case, packing-rings attached to the 10 opposite sides of said flange, and a packing-box inclosing the inner end of said tube and packing-rings, combined with a plunger within said tube engaging said packing-box, a lever pivoted in said case having one arm extending 15 opposite said box, a valve pivotally connected to an arm on said lever, and a spring to swing said valve to its seat, substantially as set forth.
3. The case 3, having a valve-seat therein and having its upper end extending beyond 20 said seat, combined with a valve of disk form shutting against said seat, the plane of whose outer side is below said upper end of the case, a lever pivoted in said case having said valve pivoted thereon, a spring engaging the under
- side of said valve, and a plunger passing 25 through the side of said case opposite one end of said lever, substantially as set forth.
4. In combination, the case 3, the lever 14, pivoted to the inner side of said case, the valve 21, pivotally attached to said lever and 30 having the arm 24 on its under side, a bar, 16, with which said arm engages, fixed across said case, and a spring engaging with said valve to close it, substantially as set forth.
5. In combination, the case 3, the lever 14, 35 pivoted to the inner side of said case, the valve 21, pivotally attached to said lever by a pin extending thereacross to one side of its center and having the arm 24 on its under side, a bar, 16, with which said arm engages, 40 fixed across said case, and a spring engaging with said valve to close it, substantially as set forth.

CHARLES HITCHCOCK.
